UNITED STATES PATENT OFFICE.

OLIVER E. WATSON, OF DAYTON, OHIO.

REINFORCING MEANS FOR AUTOMOBILE RADIUS-RODS.

1,376,058.

Specification of Letters Patent. Patented Apr. 26, 1921.

Application filed June 5, 1920. Serial No. 386,896.

To all whom it may concern:

Be it known that I, OLIVER E. WATSON, a citizen of the United States, residing at Dayton, in the county of Montgomery and 5 State of Ohio, have invented certain new and useful Improvements in Reinforcing Means for Automobile Radius-Rods, of which the following is a specification.

The principal object of my invention is to 10 provide a simple and efficient reinforcing or bracing device for the front radius rods of automobiles of the Ford type. If no brace is provided, the sudden jars to which these rods are subjected cause them to work 15 loose, and often break, at their front ends.

Another object of the invention is to provide on my reinforcing device, shoulders which are adapted to bear against the axle to protect the radius rod bolts against the 20 jars to which the machine is incident. In other words, the strain is taken off of the bolts and thrown upon the shoulders.

Other important and incidental objects will be brought out in the following specification and particularly set forth in the subjoined claims.

In the accompanying drawings, Figure 1 is a top plan view of a part of the front running gear of a Ford automobile, showing 30 my improved bracing means secured to the radius rods thereof. Fig. 2 is a bottom plan view of the apex end of the radius rod construction, showing my brace connected thereto. Fig. 3 is a cross sectional view 35 taken through the front axle, showing one end of my brace secured thereto. Fig. 4 is a front view of said axle, showing one end of the brace secured thereto. And Fig. 5 is a cross section taken on the line *a—a* of 40 Fig. 2.

Throughout the specification and drawings, similar reference characters denote corresponding parts.

Referring to the accompanying drawings, 45 the numeral 1 designates the Y-shaped radius rod of a Ford automobile, whose forked ends 2 and 3 are connected to the front axle 4 by bolts 5, 5. For the purpose of firmly bracing the radius rod construction 1, I have 50 provided the following described device which is adapted to be readily applied thereto.

This device is preferably made up of two pieces of T-iron 6 and 7. Referring to Fig. 52, the rear end of the piece 6 is notched to receive the free end of the piece 7, whereby

the stress or strain exerted upon one piece, will be firmly resisted by the other. The notch in the T-iron 6 receives the inner end of the T-iron 7 at an angle that corresponds 60 to the angle between the radius rods 2 and 3.

Each T-iron is shaped to curve downwardly from its rear portion, to bring its front end into a position beneath the axle 4 to permit one of the bolts 5 to be passed 65 through a hole in the horizontal portion of its front end. After this bolt is passed through said hole, a nut 8 is applied to it for the purpose of drawing the horizontal portion of the T-iron tightly against the 70 bottom of the axle. The middle flange portion 9 of each T-iron projects forwardly to a point where it will bear firmly against the axle 4 when the horizontal portion of the T-iron is drawn tightly against the bottom 75 of the axle by the nut. The front end of this flange portion 9, therefore, forms a shoulder which, by engaging the axle, protects the bolt against shearing stresses. (See Fig. 3.)

At its rear end, each one of the T-irons 6 and 7 is secured to its respective radius rod by a hook-shaped clamping member 10 whose bill portion firmly grips the radius rod as shown in Fig. 5. The other end of 85 the hook is threaded for projection through a hole in the horizontal portion of the T-iron, and receives below said T-iron a nut 11 which is adapted to be turned against the bottom of the latter to cause the hook end 90 of the clamping member to firmly grip the radius rod. The hook end of each clamping member 10 passes through a notch provided in the top edge of the flange portion 9 of its respective T-iron to keep said clamping 95 member from turning.

It is thus seen that my improved brace may be readily applied to the front radius rod construction of an automobile of the Ford type. Its front ends are secured to the front 100 axle below the latter by the same bolts 5 that secure the front ends of the radius rods to the top portion of said axle. Through the engagement of the shoulders 9, 9 with the axle, the bolts are protected against shearing 105 stresses. Furthermore, longitudinal stresses are received directly by the apex end of the brace, which prevents the radius rods from breaking off, or becoming bent.

Having described my invention, I claim: 110

1. In a device of the type described, the combination with the axle of an automobile,

of a Y-shaped radius rod structure, fastening elements for securing the front ends of said structure to said axle, an angle brace applied to said forked portion, and secured 5 at its front ends to the bottom portion of the axle, and shoulders on said front ends of the brace to engage the side portion of the axle for the purpose specified.

2. In a device of the type described, the 10 combination with the axle of an automobile, of a Y-shaped radius rod structure, bolts for securing the front ends of said structure to the top portion of said axle, an angle brace applied to the forked portion of said radius 15 rod structure, whose front ends are secured to the bottom portion of the axle by said bolts, and shoulders on said brace adapted to engage the side portion of said axle to protect said bolts from shearing stresses.

20 3. In a device of the type described, the combination with an axle of an automobile, of a Y-shaped radius rod structure whose forked portion is secured to said axle, a pair of T-irons, one of said T-irons having a 25 notch provided in its horizontal portion, at one end, to receive an end of the horizontal portion of the other T-iron at an angle

thereto corresponding to the angle formed by the forked portion of the radius rod structure, said T-irons secured at their front 30 ends to said axle, and hook bolts for securing the rear ends of said T-irons to the forked ends of said radius rod structure, to bring the apex of the angle formed by said T-irons within the angle formed by the 35 forked portion of said structure.

4. In a device of the type described, the combination with an axle of an automobile, of a Y-shaped radius rod structure, bolts for securing the front ends of said structure to the top portion of said axle, means for connecting the rear ends of a pair of T-irons to the rear part of the forked portion of said radius rod structure, and front horizontal extensions on said T-irons for connection to 45 the bottom of said axle by the bolts, at a point which allows the front ends of the flange portions of said T-irons to engage the side of the axle for the purpose specified.

In testimony whereof I have hereunto set 50 my hand this 29th day of May, 1920.

OLIVER E. WATSON.
